HOIT & LAFLIN.

Harvester.

No. 92,723.

Patented July 20, 1869.

United States Patent Office.

L. B. HOIT, OF CEDAR FALLS, IOWA, AND MATTHEW LAFLIN, OF CHICAGO, ILLINOIS, SAID HOIT HAVING ASSIGNED HIS RIGHT TO SAID LAFLIN.

Letters Patent No. 92,723, dated July 20, 1869.

IMPROVEMENT IN HARVESTERS.

The Schedule referred to in these Letters Patent and making part of the same.

To all whom it may concern:

Be it known that we, L. B. HOIT, of Cedar Falls, in the county of Black Hawk, and State of Iowa, and MATTHEW LAFLIN, of the city of Chicago, in the county of Cook, and State of Illinois, have invented new and useful Improvements in "Mowing and Reaping-Machines," and we do hereby declare that the following is a full and exact description thereof, reference being had to the accompanying drawing, making part of this specification, in which—

Figure 1 represents the plan,

Figure 2, the side elevation, and

Figure 3, the rear elevation of the machine.

Figure 4 is an enlarged plan of the oscillating shoe;

Figure 5, a sectional view of the connection between the finger-bar and the shoe; and

Figure 6 is a side elevation of the swivel-ring of the parallel-motion device.

Similar letters of reference, marked on the several of the above figures, denote similar or corresponding parts of the machine.

Our present invention consists of several improvements in the invention, entitled "Improvement in Reaping and Mowing-Machines," for which Letters Patent of the United States have been granted to L. B. HOIT, bearing date of January 23, 1866, and numbered 52,167; and

It consists in an oscillating shoe attached securely to the machine, serving as a point of support, and a point of attachment to the finger-bar; said shoe being so constructed and arranged as to be able to oscillate while passing over the ground, and thus to easily conform to and overcome the inequalities of the ground, independently of the finger-bar; as also permitting the finger-bar to conform to the inequalities of the ground independently of the motion of the said shoe.

The improvement consists also in a connecting rod, attached to the end of the pitman-lever by swivel-ring and hooked on to the sickle-bar, for the purpose of producing straight parallel motion, and communicating the same to the sickle-bar, while the end of the said pitman-lever is working on a curve.

It consists also in the mode of attaching the finger-bar to, and detaching the same from the said oscillating shoe, by means of a cylindrical pin secured to and between the two portions of the shoe, and the hook or clutch into which the end of the finger-bar is formed; said hook being passed under and partially around the said cylindrical pin, the two thus forming a lock, that firmly secures the bar to the shoe, while the machine is working, and facilitates the detachment of the bar from the machine, while the last is not in operation.

To enable others skilled in the art to which our invention appertains, to make and use said invention,

we will proceed to describe its construction and operation.

The eccentric-wheel A, called in HOIT's original patent, "a cam-wheel e," with its roller and pitman-lever, F, is placed, in the present machine, on the side opposite to that on which the sickle-bar is attached, for the purpose of obviating the side draught of the machine when working.

Frame B, supporting the eccentric-wheel A, is made shorter, having its rear end firmly secured to the frame of the machine by stanchion or stirrup, b.

C is the oscillating shoe, made of cast-iron, and is rounded behind, for the purpose of easily sliding over the ground when the machine is backed, and is provided with a slot, G, in front.

A curved bar, D, passes through said slot, G, and has its lower end pivoted to the loops d of the shoe, while its upper end, provided with a ring, is put over the end of the axle of the machine.

Bar D, while it drags the shoe, plays in the slot G, permitting the shoe, and the guards of the finger-bar secured to it, to oscillate up and down, and thus to conform to and overcome the inequalities of the ground.

Pin g' regulates the play of the bar D in the slot G, thus regulating the height of the guards to cut grass higher or lower.

Braces E E pinned to the frame B, and to the shoe C, keep said shoe in its proper place, and off the wheel of the carriage.

The connection of the finger-bar with the shoe is effected in an entirely novel way. Two partitions, H H, of the shoe C, form a chamber in which the end of the finger-bar snugly rests, and which hold it fast when the bar strikes against some obstruction during the work of the machine.

A cylindrical pin, I, is secured between and to the partitions H H, and the plate J secured to the end of the finger-bar is turned up in a shape of a hook or clutch, which hook, i, by passing under and partially around the cylinder I, forms a perfect lock. This arrangement forming a secure connection between the shoe and the finger-bar, permits, at the same time, a free raising or lowering of the outer end of the bar to pass it over obstructions, as also affords an easy means of attaching the finger-bar to or detaching it from the machine, and when so detached, the bar is placed on the cross-piece of the frame of the machine, where proper stanchions or hooks are placed to receive it.

The device for raising and lowering the outer end of the finger-bar, consists of an angular lever, O, having its fulcrum on the cylindrical pin I, of the shoe C, the end of its horizontal arm P being secured to the finger-bar, and its vertical arm P' connected with foot-treadle lever S by means of chain Q passing under and

around pulley R, secured to the frame of the machine, so that the driver, by pressing down the treadle T, can raise the outer end of the finger-bar.

The oscillating shoe C is so constructed as to form a recess, K, on the outside, for the purpose of placing the first guard of the finger-bar in said recess, and on the line with that side of the shoe; the object of this being to allow the knives between the first two guards to cut grass independently of the shoe, when the finger-bar is elevated at any angle, and to compel grass to fall between the said guards, thus obviating the choking of the machine.

To move the sickle-bar, a parallel-motion device is contrived. As the end of the pitman-lever F moves on a circular curve, the connecting-rod L is provided with a fork, L', screwed on its upper end, which fork contains a swivel-ring, M, pinned between and to the prongs of said fork, and is set over the end of the pitman-lever F. The lower end of the rod L is formed into a hook, l, which is hooked into the head N of the sickle-bar.

The swivel-ring M, permitting rod L to play freely and to work in straight parallel lines, although the end of the pitman F works on a curve, prevents the strain of the rod L on the sickle-bar.

The screwing of rod L into fork L' permits the rod

L to be extended or shortened according to the distance at which the sickle-bar is placed.

Having thus fully described our improvement, What we claim as our invention, and desire to secure by Letters Patent, is—

1. The oscillating shoe C, constructed with partitions H H, and recess K, and provided with the curved rods D, and braces E E, substantially in the manner and for the purpose set forth.

2. The connecting lock-joint formed by the cylindrical pin I, and hooked end of finger-bar J, constructed to operate in the manner and for the purpose set forth.

3. Giving a reciprocating motion to the sickle while in different positions, by means of the combination of the cam or eccentric-wheel A, pivoted lever F, rod L, jointed to lever F, in the manner described, and connected to the sickle-bar by the head N, substantially in the manner described.

L. B. HOIT.
MATTHEW LAFLIN.
